MOLDING APPARATUS HAVING CONTINUOUS BELT-TYPE PRINTING MECHANISM

John S. Truesdell, Los Angeles, Calif.

Application June 12, 1952, Serial No. 293,179

4 Claims. (Cl. 107—3)

1

This invention has special reference to printing apparatus for producing cavities in the beds provided in mold trays of the type employed in the manufacture of articles of confection.

In candy manufacture, it is customary, in the molding of candy bodies, to provide apparatus including open-topped trays containing a bed of starch, or other impression-receiving powdered or pulverulent material. Such trays are brought into registry with movable dies which enter the impressionable bed of material in each tray to produce therein sockets or cavities adapted for the reception of fluid body materials from which confections are made. The cavities are of different shapes so that the body material, upon cooling or solidifying therein, will take the physical form of the cavities.

Machines for producing the cavities in the molding material are known as mold printers. Hitherto most of these printers have operated on the intermittent principle; that is, the trays are advanced along a confined guideway longitudinally into vertical registry with the printing dies. When in such registry transitional movement of the trays is interrupted, so that the dies may be forced into the bed of impressionable material contained in a stationary tray in producing the candy-forming cavities therein.

It has also been proposed, as disclosed in my prior copending application, Serial No. 257,043, filed November 19, 1951, to provide continuously operating printers in which the cavity-forming dies are carried by an endless chain or belt means mounted in a machine frame above the horizontal and longitudinal plane of advance of the starch-filled trays, cooperative means being provided for effecting relatively uniform transitional movement in a common longitudinal direction on the part of the trays and the die-carrying belt means, so that while the dies and trays are moving longitudinally in unison with each other, the dies carried by the belt means may be additionally moved vertically or perpendicularly to the plane of travel of the trays. This perpendicular movement causes the dies to enter the bed of powdered material carried by each of the associated guide-confined and longitudinally moving trays to a regulated extent, thereby forming confection-receiving cavities in said powdered material.

While such a continuously operating printer is able to produce a given number of finished molds at a higher rate of speed than the intermittent type of printer, nevertheless the continuous printer has not been altogether satisfactory. In part, at least, this is attributable to the matter

2

of providing apparatus which will function in a smooth, uniform, non-vibratory and shock-avoiding manner. It will be understood that shock and vibration in a machine of this kind are undesirable, since the same interferes with the operation of the printer in its ability to produce sharply and definitely defined cavities in the starch or other powdered material comprising the cavity-receiving bed of a molding tray.

It is, therefore, a primary object of the present invention to provide a continuous mold-printing machine in which dies are carried by an endless belt and wherein improved means are provided for effecting without jar or vibration vertical movement of the dies while traveling into and out of engagement with the impressionable beds of molding trays.

It is another object of the invention to provide mold-printing apparatus of the character set forth in which the dies are mounted for movement in unison with a frame-supported endless belt means and wherein the dies are advanced into and removed from engagement with tray beds by improved frame-carried cam means which cooperate with the dies to produce positive and controlled movement thereof toward and away from associated mold trays.

Other objects of the invention are to provide a continuous mold-printing apparatus in which belt-carried printing dies are moved into and out of engagement with the beds of associated molds through the action of reversely disposed frame-carried cam devices; to provide cam devices which cooperate with wedge elements formed on the ends of spring-pressed die-carrying bars or strips, the arrangement being such that as the die bars or strips are advanced longitudinally in unison with the associated molds by the operation of a supporting endless chain or belt, the engagement of the wedge elements on said bars with the cam devices producing easy, positive and non-jarring movement of the die elements of said bars both into and out of the impressionable material contained in the molds; to provide apparatus of this character in which the wedge elements are carried by the die element-supporting bars are disposed in pairs at each end of each of said bars, the wedge elements presenting reversely inclined surfaces which conform to the inclination of the associated contacting surfaces of the stationary cam devices employed in imparting mold-bed penetrating movement to the die elements; and to provide mold-printing apparatus for the production of confectionery articles wherein said apparatus

possesses a higher capacity for producing finished molds than prior apparatus of this nature.

For a further understanding of the invention, reference is to be had to the following description and the accompanying drawings, wherein:

Fig. 1 is a side elevational view, partly in vertical longitudinal section, of a continuous mold-printing machine formed in accordance with the present invention;

Fig. 2 is a horizontal sectional view taken through the machine on the plane indicated by the line 2—2 of Fig. 1 and disclosing more particularly the arrangement of the laterally off-set cam rails and the cooperative wedge elements of the die bars of the machine;

Fig. 3 is a vertical transverse sectional view taken on the line 3—3 of Fig. 1;

Fig. 4 is a detail perspective view showing one of the die bars and wedge elements carried at each end thereof.

Referring more particularly to the drawings, there has been disclosed at 1 a frame structure which, in this instance, comprises rigidly connected, vertically extending and transversely spaced side members 2 and a horizontally and longitudinally extending table 3, the latter being arranged between the side members 2. The upper surface of the table 3 is provided with transversely spaced longitudinally extending guide strips 4 which, in association with the table, provide a longitudinally disposed guideway for the reception and longitudinal advance of a plurality of open-topped mold trays 5.

The bottom of each of these mold trays, contiguous to the ends of each tray, is provided with uniformly spaced transversely extending cleats 6. These cleats are disposed for engagement with dogs 7 which are carried by and disposed in uniformly spaced longitudinal order on a pair of drive chains 8, the latter passing around sprockets 9 fixed upon transversely extending frame-journalized shafts 10. One of the shafts may be provided, as shown, with a pulley 11, by means of which rotating power is imparted to the shafts in driving the chains 8. The sprockets and chains are disposed in vertical registry with longitudinally disposed slots 12 formed in the table 3. The spacing of the dogs 7 is such that the same engage with the rear surfaces of the forwardly disposed cleats 6 of each mold tray, whereby when power is imparted to the chains 8, the engagement of the dogs 7 with the cleats 6 will cause longitudinal advance of the trays 5 along the guideway G provided longitudinally for said trays by the frame structure. The direction of advance of the trays along said guideway is indicated by the arrow b, as shown in Fig. 1.

The trays each include relatively shallow, rectangular flat bottom devices, the same being formed with short upstanding marginal walls 13 which produce in the trays shallow compartments or chambers adapted for the reception of a finely divided powdered or pulverulent material, such as starch, or other farinaceous substances. With the trays filled with starch or the like, as shown in Fig. 1, and advancing along the guideway G, the apparatus of the present invention provides printing mechanism adapted for producing in the mold beds, indicated at S, a plurality of cavities shown at C. In these cavities candy-forming material in a fluid or formative state may be introduced for the molding of candy articles of desired configuration.

This printing mechanism, which is indicated in its entirety by the letter P, comprises in a pre-

ferred embodiment a pair of horizontally and transversely extending, longitudinally spaced shafts 14, the latter being suitably journaled for rotation in bearings 15 carried by the side members 2. In this instance one of the shafts 14, as shown in Fig. 3, is equipped at one end with a sprocket or its equivalent 16, by means of which power applied to the sprocket may be used to effect rotation of the shafts 14 and the endless belt mechanism associated therewith.

Each of the shafts 14 is equipped with a pair of sprockets 18 which are arranged within the confines of the side members 2. Passing around the teeth of the sprockets 18 are a pair of vertically situated, transversely spaced, endless chains or belts 19. In this instance the chains or belts have been shown as being of the link type, and each pair of transversely registering links has suitably joined therewith the ends of a transversely extending die-carrying strip 20. The pintle pins 21, used in articulately uniting the ends of the links comprising the chains 19, are preferably extended, as shown in Fig. 3, in order to have their outer extended ends equipped with rollers 22, the latter being adapted to ride on horizontally disposed guide angles 23 which are stationarily positioned on the frame structure 1.

Each of the strips 20 is formed with a pair of longitudinally spaced openings disposed in registry with opening formed in bearing sleeves 24 mounted on each strip. Slidably positioned in these openings are stems 25 carried by hubs 26 which are mounted on and project rigidly from the intermediate portions of a plurality of die-carrying bars 27. The sleeves 24 constitute seats for the reception of coil springs 28, the latter surrounding the stems 25 and contact with nut-held members 29 threaded on the outer ends of the stems 25. The springs tend to expand until the ends of the hubs 26 contact with the strips 20 as shown at the top of Fig. 3, thereby maintaining the strips 20 and the bars 27 in spaced parallel order. Each of the bars 27 is provided with a die 30 which includes a plurality of cavity-forming projections 31.

In order to move the projections 31 of the dies 30 into cavity-producing engagement with the bed S of each of the molding trays as the latter move in unison with the printing dies, each of the strips 27 has formed at each end thereof a pair of oppositely disposed inner and outer wedge elements 32 and 33, respectively. Each of these elements is formed with a surface disposed in a plane angular to that of the bar surface on which the wedge elements are formed.

These wedge elements are shaped and positioned for engagement with stationary cam rails 34 which are carried by and form a part of the frame structure. As shown in Figs. 1 and 2, the cam rails which are arranged on each side of the frame structure, are positioned in reversely extending oppositely disposed order. The forward cam rail, indicated at 34a, has its bottom surface 34b inclined downwardly and rearwardly from the thin forward end 34c thereof to the flat and thickened rear edge 34d. The companion cam rail 34e at each side of the frame has its lower surface 34f disposed to extend in an angular upward direction from the thickened flat forward end 34g thereof toward the relatively thin rear edge 34h.

By reference to Fig. 2, it will be noted that the rail 34a at each side of the frame is disposed closely adjacent the side member 2, whereas the

associated cam rail 34e is arranged laterally inwardly and to one side of the rail 34a, the rail 34e being carried by the extension elements disclosed at 35. This arrangement of the cam rails is done in order that the rails 34e will register with the inner wedge elements 32 of the bars 27, while the cam rails 34a will be disposed above and in vertical registry with the outer wedge elements 33 of the bars 27.

The inclination of the surfaces of the wedge elements 33 corresponds with the surfaces 34b of the cam rails 34a. Likewise, the inclination of the outer surfaces of the wedge elements 32 corresponds with the inclination of the surfaces 34f of the cam rails 34e.

In the operation of the machine, as the starch-filled mold trays move along the guideway G of the frame structure into registry with the upwardly disposed printing mechanism P, the printing dies supported by the lower run of the conveyor belt 19 are, first, by the action of the wedge-shaped cam rails 34a, forced downwardly and outwardly against the resistance offered by their coil springs 28. This operation causes the die projections 31 to enter the starch bed contained in the mold tray, as shown in Fig. 3, thereby producing the cavities C in said bed. When the cavities are fully formed the die projections 31 are gradually released from contact with the mold beds by the engagement of the wedge elements 32 with the surfaces 34f of the rails 34e. This result is accomplished in a manner avoiding any undue jarring or vibrating on the part of the mold trays, so that there will be no undesired or imperfect formations produced in the die-formed shapes of the mold cavities. The arrangement of the rails 34b and 34e is such that the wedge elements 32 and 33 are in joint contact therewith as said wedge elements pass from engagement from one set of said cam rails to the next. This construction avoids the abrupt or sudden removal of the dies from engagement with the mold beds, as in the construction set forth in my above identified co-pending application, thereby resulting in the formation of more perfectly developed mold cavities.

I claim:

1. Printing mechanism for producing molding cavities in the beds of molds utilized in producing articles of confection comprising: a frame structure having a longitudinal guideway, means for advancing a plurality of molds in longitudinally aligned closely succeeding order along said guideway, endless belt means arranged above said guideway, printing dies carried by said belt means in longitudinally spaced positions thereon for registry with the molds on said guideway, means carried by said belt means supporting said dies in connection therewith for movement in directions generally perpendicular to the plane of movement of the belt means, spring means retaining said dies in withdrawn non-printing positions in connection with the supporting means thereof, and relatively stationary cam devices carried by said frame structure and cooperative with said die-supporting means to produce perpendicular movement of said dies and in opposition to the forces exerted by the spring means when the dies are brought into printing registry with the molds on said guideway, said cam means including reversely disposed inclined surfaces engageable with said die-supporting means to produce gradual movement of the dies when traveling into and out of cavity-producing engagement with molds supported on said guideway.

2. Apparatus for producing confection-forming molds, comprising: a frame structure provided with a longitudinally extending guideway formed for the reception of a plurality of flat, shallow, open-topped mold trays, each of said trays containing a bed of a powdered material adapted for the formation of confection-molding cavities therein, means for producing sustained uninterrupted longitudinal movement of said trays in adjacent order along said guideway, continuously operating printer mechanism carried by said frame structure and disposed above the trays positioned on the guideway, said printer mechanism including an endless belt supported by said frame structure, said belt having a lower run movable longitudinally of and in parallel adjoining relationship with said guideways and the mold trays disposed thereon, printing dies carried by said endless belt at spaced longitudinal intervals, means supporting said dies for sliding movement in connection with said belt perpendicularly thereof and toward and away from the beds of said trays when said dies are brought into registry therewith, spring means cooperative with said dies to maintain the same normally in withdrawn non-printing position with respect to said trays, cam means stationarily carried by said frame structure and cooperative with said die-supporting means to produce movement of said dies against the opposition of said spring means and into and out of engagement with the beds of said trays while said dies and trays are traveling in relative registry and with the lower run of said belt longitudinally of said guideway, said cam means having reversely disposed inclined surfaces arranged longitudinally of said guideway, and wedge elements carried by said die-supporting means arranged to engage said cam means in a manner causing the dies to be brought gradually into cavity-printing engagement with the molding material of said trays and gradually removed therefrom while the dies are traveling in cavity-forming unison with the mold trays.

3. Printing mechanism for producing cavities in moldable beds of confection-forming mold trays, comprising: a supporting structure having a longitudinal guideway, a plurality of flat shallow mold trays positioned in train-forming order on said guideway and movable in unison longitudinally thereof, each of said trays being formed with an open-topped chamber for the reception of a body of an impression-receiving molding material, an endless longitudinally extending belt means carried by said supporting structure and having a lower run positioned above and in spaced parallel relation to said guideway and the trays positioned thereon, said lower run being movable in the same direction and at the same linear speed as said trays, a plurality of transversely extending die-supporting bars formed with bearing sleeves, transversely extending die-carrying strips provided with stems slidably mounted in the bearing sleeves of said bars, spring means cooperative with said bars and stems and operative to apply forces to said strips in positions removed from printing contact with molding material present in the associated trays, a pair of transversely spaced, oppositely facing, stationary cams carried by said supporting structure and extending longitudinally thereof on each side of said guideway throughout substantially the full length of the lower run of said belt, said cams being formed to present reversely inclined surfaces, and a pair of cooperative, reversely inclined wedge elements carried by each end of each

of said strips, said wedge elements contacting the inclined surfaces of said cams to move the strip-carried dies into full cavity-printing contact and formation with said moldable tray material in a manner effecting gradual movement of the dies into and out of said mold material in the formation of the cavities therein while the mold trays are moving in unison with the lower run of said belt means.

4. In a continuous press for producing cavities in candy-forming molds, said press being of the type having a frame structure formed with a longitudinally extending guideway for the slideable reception of a plurality of shallow, flat, open-topped mold trays containing pressure-placeable molding material; means for advancing said trays without interruption and at a predetermined rate of linear travel along said guideway, a pair of parallel sprocket-carrying shafts journaled for rotation in connection with said frame structure above said guideway, a pair of transversely spaced, parallel, longitudinally extending, endless chains trained around the sprockets of said shafts, longitudinally spaced, transversely extending bars secured at their ends to said chain, said bars being formed with bearing sleeves, die-carrying strips provided with stems slidably mounted in the bearing sleeves of said bars, spring means cooperative with said bars and stems and serving to apply forces to said strips which normally maintain the printing dies of said strips in positions removed from printing contact with the molding material present in the associated trays, elongated stationary cam members

carried by said frame structure and disposed above the molds on said guideway, there being two of said cam members at each side of said guideway and which are disposed in transversely offset relationship with respect to each other, having reversely inclined surfaces, and a pair of wedge elements mounted at each end of said die-carried strips disposed for registry with the pairs of cam members arranged at each side of said guideway for selective engagement therewith, relative engagement between said cam members and wedge elements serving to move said die strips gradually against the resistance of said spring means into and out of cavity-printing contact with the molding material of said tray during longitudinal advance of the printing dies in registry with said trays.
